HARRY C. COTTER AND GEORGE G. GREENE, OF FORT WAYNE,
INDIANA.

Letters Patent No. 83,834, dated November 10, 1868.

IMPROVED SAFETY-SWITCH LOCK.

The Schedule referred to in these Letters Patent and making part of the same.

To all whom it may concern:

Be it known that we, HARRY C. COTTER and GEORGE G. GREENE, of Fort Wayne, in the county of Allen, and State of Indiana, have invented certain new and useful Improvements in Safety-Switch Locks; and we do hereby declare that the following is a full and exact description thereof, reference being had to the accompanying drawings, and to the letters of reference marked thereon, in which like letters refer to like parts in the different figures.

To enable others skilled in the arts to make and use our invention, we will proceed to describe its construction and operation.

In the drawings—

Figure 1 is a vertical section.

Figure 2 is a plan view.

The nature of our invention consists in an improvement in method of constructing switch-locks.

A represents a horizontal bar, upon the outer edge of which are mounted stops or catches, *a a' a'' a'''*. Said catches work through guard B, as seen in the drawings, fig. 2. Said bar A, in its operation, moves laterally, and is actuated by means of spiral springs *b b*, which serve to force stop *a* forward to the position seen in fig. 2.

C represents one or more eccentric-levers, which are pivoted at *c c*, and are connected and pivoted together by bar D, as seen at *e e* in fig. 2.

E represents a vertical axle, whose centre is positioned on a line with and equidistant from pivots *e e*.

f represents an arm, which extends horizontally and at right angles to axle E, and is pivoted to bar D at a point in line with and equidistant from pivot *e e*. (See fig. 2.)

g represents a handle, which extends horizontally backward at right angles to axle E, and is used in operating the apparatus, as will be described.

Eccentric-levers, C, are each provided with an eccentric-recess, *h h*, constructed in the form seen in the drawings, fig. 2, through which a stud or pin, *i*, passes.

The outer edge of said recesses is so formed that when the handle or lever *g* is carried around so as to stand at right angles to the bar D, then the eccentric-levers C C are also brought to the same angle, and the surface, *j*, in said recess, bears directly on stud *i*, and the said studs, together with stop-bar A, are drawn backward in a parallel line, and thus the lever F is relieved, and may be forced in either direction.

K represents arms, which are formed on and extend forward from the eccentric-levers, through the guard B,

and into slot G, in which the lever F moves. Now, it is clear that when the stops *a* are withdrawn from slot G, so as to relieve the lever F, the arms K extend across the said slot, and will intercept the movement of said lever F. But said eccentric and arms are so constructed and held in position that a slight pressure of the lever throws them off their centres, and the spring-pressure of stop-bar A impels it forward in such a manner as to carry the outer end of the lever K to the position seen in the drawing, fig. 2, and thus the catches are forced out, and across the slot G, to the position seen in fig. 2. At the same time the lever F must be continued in its forward movement until it strikes the inclined surface of stop *a*, which yields easily to the pressure, and is thereby thrown back far enough to let the lever pass when it comes forward, thus effectually securing it in the desired position.

H represents a stop-bar, which is positioned as seen in fig. 2, and is provided with a recess, *m m*, through which rods, *n n*, may pass freely when in range. This bar receives a reciprocating motion, and is so operated, by a key or any other mechanical device, that when the key is removed from the apparatus, the stop-bar is so positioned that the apertures *m m* are thrown out of range with the rods *n n*, and they consequently cannot be forced backward, the result of which is, that the stop-bar and catches *a* are securely locked in position. Recesses *m m* cannot be brought in range with rods *n n* except by the use of the key. Said switch cannot be adjusted unless a key is used, and the key cannot be removed or the switch locked unless the switch-lever is in the desired position.

The advantages of this switch-lock are, its entire safety, durability, and effective operation, it being impossible to remove the key from the lock until the lever is adjusted to the desired point, and when once locked, it is perfectly secure.

What we claim as new, and desire to secure by Letters Patent, is—

Stop-bar A, carrying stops *a a' a'' a'''*, and eccentric-levers C C, in combination with the stop-bar H, having recesses *m m*, the whole being constructed in the manner and for the purpose substantially as set forth and described.

H. C. COTTER.
G. G. GREENE.
